D3-15

AU 292

EX

OR D 11,696

DESIGN.

S. HEITER & S. J. LESEM.

Umbrella Handle.

D
D. 11,696.

Patented Mar. 23, 1880.

ATTEST:

Julian A. Kourdele
Arthur C. Fraser.

DESIGNERS:

Simon Heiter
Solomon J. Lesem
By G. Howell
Attorney.

UNITED STATES PATENT OFFICE.

SIMON HEITER AND SALOMON J. LESEM, OF NEW YORK, N. Y.

DESIGN FOR AN UMBRELLA-HANDLE.

SPECIFICATION forming part of Design No. 11,696, dated March 23, 1880.

Application filed February 5, 1880. Term of patent 3½ years.

To all whom it may concern:

Be it known that we, SIMON HEITER and SALOMON J. LESEM, citizens of the United States, and both residing at New York, in the 5 county and State of New York, have invented and produced a new and original Design for Parasol and Umbrella Handles, of which the following is a specification, reference being had to the accompanying drawing, forming part 10 thereof.

The object of our invention is to produce a novel and fanciful design for the handles of umbrellas or parasols; and it consists in giving to the head of the handle the configuration 15 of a serpent.

In the accompanying drawing a side view serves to fully illustrate a handle which embodies our peculiar design.

a represents the body of a preferably round 20 handle. At the point b it bends abruptly, and, decreasing in size, assumes the semblance of a coiling reptile as it turns backward, and terminates in a serpent's head, c. A carved line, d, in relief, springing from the front of the 25 handle and losing itself in a vanishing curve, has the effect of causing the serpent to appear as if it were bursting forth and gradually emerging from the interior of the handle.

The head of the serpent is appropriately 30 carved, and the ornamentation increased by the insertion of precious stones for eyes.

The spherical carving e is designed to represent fruit which the serpent is in the act of biting.

Any appropriate carving may be used on 35 the body of the serpent, and the form or outline may be somewhat varied without departing from the leading features of our design.

What we claim as a new design is—

1. The design for an umbrella or parasol 40 handle, the same consisting of the representation of a serpent issuing forth from the upper part of the handle, substantially as described, and shown in the accompanying drawing.

2. The design for a parasol or umbrella handle which consists of the representation of a 45 serpent issuing forth from and coiling backward over the top of the handle, as described, and shown in the accompanying drawing.

3. The design for the handle of an umbrella 50 or parasol which consists of the representation of a serpent issuing from the handle, coiling round in a serpentine manner, and in the act of biting, as described, and shown in the accompanying drawing.

SIMON HEITER.
SALOMON J. LESEM.

Witnesses:

FRDK. RAACKE,
S. S. GLEN.